Primary Examiner — T. Chase Nelson*Assistant Examiner* — Eric Goodman(74) *Attorney, Agent, or Firm* — David M. Fortunato; The Webb Law Firm(57) **CLAIM**

The ornamental design for a safety blood collection assembly, as shown and described.

DESCRIPTION

FIG. 1 is a perspective view of a tube holder of a safety blood collection assembly;

FIG. 2 is a top view of the tube holder of the safety blood collection assembly of FIG. 1;

FIG. 3 is a left side view of the tube holder of the safety blood collection assembly of FIG. 1;

FIG. 4 is a front view of the tube holder of the safety blood collection assembly of FIG. 1;

FIG. 5 is a rear view of the tube holder of the safety blood collection assembly of FIG. 1;

FIG. 6 is a right side view of the tube holder of the safety blood collection assembly of FIG. 1; and,

FIG. 7 is a bottom view of the tube holder of the safety blood collection assembly of FIG. 1.
